U. S. PATENT OFFICE.

No. 61.

1861.

WHOLE No. 1,426.

Trade Mark.

ALBERT F. JOHNSON, OF BOSTON, MASS.

Letters Patent for a Design, No. 61, dated May 28, 1861.

SPECIFICATION.

TO ALL PERSONS TO WHOM THESE PRESENTS SHALL COME:

Be it known, that I, ALBERT F. JOHNSON, of Boston, in the county of Suffolk, and State of Massachusetts, have invented or produced a design to be used as a Trade Mark on Sewing Machines; and I hereby declare the same to be fully described in the following specification, and represented in the accompanying drawing.

In carrying out my invention, I have adopted the fac simile of a gold medal as awarded to me by the Massachusetts Charitable Mechanic Association, held in Boston during the fall of 1860, and I have combined therewith the word "Gold Medal Sewing Machine," in manner as shown in the drawing. The devices on the said medal consist: first, of three plain rings or circles, they being drawn concentrically with respect to the outer edge of such medal, and near thereto, as shown in the drawing. Within the inner circle or ring are the words "The Mass. Charitable Mechanic Association, award to A. F. Johnson for the Best Sewing Machines, Exhibition of 1860;" the same being arranged therein and ornamented in manner as delineated in the drawing. Over and with the said configuration and words, I arrange and combine the words "Gold Medal Sewing Machine," the same being disposed in circles or lines concentric with those first mentioned, the whole thus combined and arranged constituting my trade mark.

I claim the above combination and arrangement of words and ornamental

Johnson's Design for a Trade Mark.

devices for a trade mark to be applied to sewing machines, the same being as above described, and as represented in the accompanying drawing.

A. F. JOHNSON.
